RICHARD VAN DOHLAN, OF ALBUQUERQUE, NEW MEXICO, ASSIGNOR OF ONE-HALF
TO LOUIS P. HILDERBRAND, OF COOLEY, ARIZONA.

DESIGN FOR A WATCH-CHAIN.

59,307.

Specification for Design.

Patented Oct. 4, 1921.

Application filed October 9, 1920. Serial No. 415,913. Term of patent 14 years.

To all whom it may concern:

Be it known that I, RICHARD VAN DOHLAN, a citizen of Holland, residing at Albuquerque, in the county of Bernalillo and State of New Mexico, have invented a new, original, and ornamental Design for a Watch-Chain, of which the following is a specification, reference being had to the accompanying drawings, forming a part thereof.

The figure is a perspective view of the watch chain showing my new design.

I claim:

The ornamental design for a watch chain, as shown.

RICHARD VAN DOHLAN.
